NONREFILLABLE BOTTLE STOPPER

James H. Baldwin, New Milford, and Knud Knudsen, Danbury, Conn., assignors to Container Fitments, Inc., New York, N. Y., a corporation of Maryland

Application December 23, 1936, Serial No. 117,396

14 Claims. (Cl. 215—22)

This invention relates to non-refillable bottle stoppers and more particularly to the construction and assembly of that type of non-refillable bottle stopper that has a so-called float valve.

5 One of the objects of this invention is to provide a non-refillable bottle stopper construction which will be of inexpensive manufacture, characterized by facility of assembly, and that will be strong and durable. Another object is 10 to provide a non-refillable bottle stopper of the above-mentioned character in which component parts may be manufactured at low cost and be capable of ease and low cost of assembly. Another object is to provide a stopper and bottle neck construction in which the mounting of the 15 non-refillable stopper with respect to the bottle neck will be simple and inexpensive to accomplish in practice, strong and dependable, dependably resistant to removal, and reliable in actual 20 use.

Another object is to provide an efficient, lasting and dependable closure or seal to negative leakage of the bottle contents during, for example, shipment or transportation, while at the 25 same time avoiding interference with the non-refillable stopper construction and its intended action. Another object is to provide a bottle neck or like container part and a non-refillable stopper construction with a closure and sealing 30 means by which leakage of the liquid contents is dependably prevented. Another object is to provide a construction of the above-mentioned character in which a sealed connection between the stopper construction and the bottle neck or 35 the like is dependably supplemented by a bottle closure and sealing means to insure against loss or leakage of liquid contents.

Another object is to provide a construction of the above-mentioned character in which the 40 "pour" of liquid out of the bottle or container is smooth, adequately rapid, and neat. Another object is to provide a non-refillable stopper construction in which a long-lasting and dependably acting seal or closure is achieved in order 45 to negative dependably attempts to refill the container or bottle under the production of a pressure differential between the outside and inside of the bottle. Another object is to provide a non-refillable stopper construction that is dependably tamper-proof and yet compact and durable in construction and efficient in action.

The invention accordingly consists in the features of construction, combinations of elements and arrangements of parts as will be exemplified 50 in the structure to be hereinafter described, and

the scope of the application of which will be indicated in the following claims.

In the accompanying drawings in which is shown one of the various possible embodiments of our invention:

Figure 1 is a central vertical sectional view through a bottle neck with the stopper and seal or closure;

Figure 2 is a plan view, as seen from the top in Figure 1, with the closure removed, more 10 particularly as seen along the line 2—2 of Figure 1;

Figure 3 is a sectional view like that of Figure 1, with the closure or seal removed, the construction being tilted through 90° from the 15 position of Figure 1, to show certain actions that take place;

Figure 3a a view like that of Figure 1 with certain parts omitted or broken away, showing a modified form of closure or seal;

Figure 4 is a transverse sectional view of the stopper construction as seen along the line 4—4 of Figure 1;

Figure 5 is a transverse sectional view of the stopper construction as seen along the line 5—5 25 of Figure 1;

Figure 6 is a transverse sectional view of the stopper construction as seen along the line 6—6 of Figure 1;

Figure 7 is a transverse sectional view of the 30 stopper construction as seen along the line 7—7 of Figure 1;

Figure 8 is a detached isometric view of one of the parts of the stopper construction, and

Figure 9 is a detached isometric view of another part thereof.

Similar reference characters refer to similar parts throughout the several views in the drawings.

Referring first to Figure 1 of the drawings, we 40 provide an outer shell or casing 10 generally cylindrical and of a diameter to be snugly received within the bottle neck 11 and to by-pass a ring-like shoulder 12, shaped as shown, extending about the inner wall of the bottle neck 45 thereof. At its lower end the casing or shell 10, made of suitably thin sheet metal, has a bottom 14 provided with a central round hole 15, but the bottom 14 has a ring-like portion 16 50 thereof that extends about the hole 15 inclined downwardly, and hence presenting an upwardly exposed face or surface that is substantially frusto-conical.

The substantially horizontal portion of the 55

bottom wall 14 forms an annular seat for receiving an annular gasket or washer 17 made of a material which preferably is per se yieldable or resilient and which is relatively easily bendable, having preferably a springy or resilient characteristic so that, when bent, it returns to normal or unflexed condition; various materials having these preferred characteristics are available, such as rubber, cork composition, cork, and the like. Preferably, and illustratively, the washer 17 is made of cork. Its outside diameter is commensurate with the inside diameter of the shell 10 and it has an opening 18 of a diameter just about equal to that of the hole 15. Normally it rests on the horizontal portion of the bottom wall 14 and it is to coat with a hollow ball valve 19; its inner annular portions overhang the frusto-conical flange or seat 16, as shown in Figure 1, and normally its action is analogous to that of a cantilever in so far as it offers support, under normal conditions, to the ball 19 and an overbalanced weight member 20 that coats with the ball 19.

Resting above the washer 17 is a thin sheet metal washer 21 whose radial dimension is commensurate with that of the horizontal portion of the bottom wall 14. Washer 21 is held against upward displacement by means later described and with the horizontal portion of the bottom wall 14 it coats to hold the resiliently flexible washer 17 in position but with the inner annular portion thereof free to partake of bending or flexing, as will be later described; these two parts thus insure the above-mentioned cantilever type of support for the washer 17 and, if desired, the metal washer 21 may be shaped to be frusto-conical or upwardly concaved, as indicated in Figure 1, to allow for greater freedom of flexing downwardly of the inner annular portion of the washer 17 under certain circumstances.

As above pointed out, the shell or casing 10 is preferably cylindrical and at its upper end it is provided with a substantially horizontally outwardly extending flange 22 whose outside diameter is substantially equal to the outside diameter of the annular shoulder 12 in the bottle neck 11, these parts thus preventing the construction from falling into the bottle; ultimately, and as later explained in detail, the flange 22 and shoulder 12 are to coat with a washer-like gasket 23 to effect a sealed connection between the casing 10 and the bottle neck.

The shell or casing 10 will thus be seen to be of a construction capable of easy and inexpensive manufacture; for example, it may be easily drawn into the form described. Preferably, however, and preferably in the course of such forming or drawing operations, the cylindrical side walls of the lower half of the shell 10 are given, throughout a suitable number of peripheral intervals, illustratively three, a slightly smaller radius of curvature as throughout the regions A, B and C of Figures 6 and 7, thereby forming or providing, throughout the lower half of the shell 10 and upon the inside thereof, a corresponding number of intervening vertically extending channels 24, 25 and 26. Where three such channels are provided, they are of a peripheral or arcuate extent somewhat less than one-sixth of the circumference of the shell 10. Preferably they are of a depth commensurate with the thickness of the sheet metal employed.

These three channels 24, 25 and 26 serve to receive three sheet metal members 28, 29 and 30, respectively, and to space them preferably equi-

distantly about the interior of the shell 10. These members are the same in construction, the details of which are best shown in Figure 8. They are made of sheet metal preferably of the same thickness as that of the shell 10.

Thus, each of these members comprises an upright portion 31 of a vertical dimension slightly less than the inside depth of the shell 10 (Figure 1) and curved to have a radius of curvature to match that of the inside surface of the shell 10.

At the two vertical side edges of the upright portion 31 and integrally formed therewith are flanges 32 and 33 extending approximately at right angles to the plane of the portion 31. These flanges 32, 33 terminate short of the bottom edge 34 of the upright portion 31 so that when the three members 28, 29 and 30 are assembled to the shell 10, these bottom edges 34 contact the shell bottom wall 14 and engage the peripheries of the metal washer 21 (Figures 1 and 7) and of the cork washer 17, while the lower ends of the side flanges 32, 33 of all three members project inwardly over the metal washer 21 (Figure 1), hold the latter against upward displacement, and thus cause it and the bottom wall 14 to hold the washer 17 in position as already above described.

The flanges 32, 33 (Figure 8) are similarly shaped; thus, each has a lower portion of appropriate radial extent to provide a straight edge face 35 parallel to the axis of the casing 10, each edge face 35 being preferably neatly squared off, as indicated. Accordingly, when the three members 28, 29 and 30 become related to the casing 10, as above described, there are thus presented toward the ball valve 19 six parallel straight edge faces 35 substantially equidistantly spaced (see Figure 7) about a circle whose radius is substantially the same as or slightly less than that of the ball member 19 itself. But preferably the flanges 32, 33 of these three members extend each at an angle to the radius drawn from the axis of the casing 10 or ball 19 to its edge face 35, and hence, as is better shown in Figure 7, the ball 19 engages or is tangent to the line in which the edge face of each flange member intersects with the inside face of the flange itself. In effect, therefore, the lower flange portions of the members 28, 29 and 30 provide a plurality of parallel knife edges along which the ball valve 19, which is hollow and has a certain degree of buoyancy, may move, insuring not only minimum frictional resistance to movement of the ball, but also other advantages later pointed out. Whichever of these lower flange portions that the ball 19 engages, the engagement with each is in substantially a true geometric point of tangency.

As shown in Figure 8, the flanges 32, 33 each has an intermediate portion which provides an edge face 36 which, however, extends at an angle to the axis of the casing 10 (see Figures 1 and 3). These intermediate portions are to coat with the weight 20 (Figures 1 and 3), the weight being given in general a concavo convex shape, substantially as shown. It is of metal and its shape effects such a distribution of weight that it is in unstable equilibrium if it is attempted to stand it up on its maximum-diameter edge. Toward the latter are presented the inclined edge faces 36, as is better shown in the sectional view of Figure 6, and for reasons that will now be clear, any contact of the outer convex or peripheral surface of the weight 20 with any of the flange or rib portions 36, is a point contact in that the portions 36 present to the weight 20 what is in effect a knife edge.

The upper end of each of the vertical flanges 32, 33 (Figure 8) is notched, as at 37 and 38, thus providing three tongues 39, 40 and 41. With these tongues and notches certain other parts contact, and among them is a member generally indicated by the reference character 43 in Figure 9 and a member 44 better shown in Figures 1 and 3. Member 44 is generally disk-shaped, is made of sheet metal, and it has a bottom 45 about the periphery of which extends a flange 46 that snugly takes into the notches 37 of the flanges 32, 33 of the members 28, 29 and 30 (see also Figure 5); it thus holds the latter against movement toward the axis of the casing 10 and takes part in insuring that these three members and their parts are held in proper alinement.

The member 44 is imperforate and preferably, at its central portion, is formed to provide an upstanding part 47 in the shape of a truncated cone. By itself it will be seen to be a simple and inexpensive part to manufacture.

The member 43 of Figure 9 is preferably a unitary sheet metal part, has a cylindrical side wall 49 which, from its upper periphery, merges into a curved mouth-like portion 50.

Its cylindrical side wall 49 is of a radius of curvature somewhat less than the radius of curvature of the inside faces of the upright portions 31 of the three inserted members 28, 29 and 30, and in effect is of a radius of curvature intermediate of the radii of curvature of the flange 46 of the member 44 and of the casing 10 itself (see Figures 1 and 5).

Extending vertically from its lower edge (see Figure 9) are pairs of slots 51—52 spaced apart sufficiently to receive therein the upper end portions of the flanges 32, 33, respectively there being one pair of such slots for each pair of such flanges.

The cylindrical wall 49 of the member 43 (Figure 9) is provided also with suitable apertures. Thus, the wall portions 53 thereof that intervene adjacent pairs of slots are provided with openings 54 and the wall portions 55 that intervene the slots of each pair are provided with holes 56. Additionally, the slots 51, 52 may terminate in elongated openings 57.

The member 43 is positioned inside of the theoretical cylinder of which the curved upright wall portions 31 of the members 28, 29 and 30 form a part and is supported against displacement in an axial direction by these upright members. Thus, the tongues 41, 41 of the flanges 32, 33 extend over the horizontal portion (see Figure 1) of the internal spout-forming part 50, while tongues 39, 40 of each flange project inwardly through the vertical slots 51 or 52, as the case may be, of the member 43, the six pairs of tongues 39—40 being thus presented interiorly of the cylindrical wall portion 49 (see Figure 5) for the support of the member 44, as above described. The slots 38, 38 (Figure 8) are of a vertical dimension to snugly receive therein so much of the cylindrical wall portion 49 (Figure 9) as extends between the upper edge of the apertures 57 and the upper edge of the cylindrical wall 49 itself. The resultant relationship of these assembled parts is best shown in Figure 1.

In effecting this assembly, a preferred procedure, again referring to Figure 1, is to position the washers 17 and 21 in the bottom of the casing 10, followed by the insertion of the ball valve 19. The upright members 28, 29 and 30 may then be assembled as a sub-unit with respect to the members 43 and 44 and the weight 20, and

this sub-unit is then slid into the casing 10, the three upright members entering the channels 24, 25 and 26, respectively (see Figures 6 and 7), and the lowermost edges of the flanges 32, 33 of these three upright members engaging the upper face of the metal washer 21 (Figure 1) to hold it and the gasket-like washer 16 in the relationships already above described.

It will be seen that the three members 28, 29 and 30 terminate above the horizontal portion 10 of the spout or mouth 50, presenting, as better appears in Figure 4, three equidistantly spaced U-shaped parts.

Thereupon, we insert, preferably with a friction fit, a top member, generally indicated by the reference character 60 in Figure 1; this top member 60 has a cylindrical side wall 61 which is snugly, and, as noted, with a friction fit, received into the upper end of the cylindrical shell or casing 10 to a depth determined by an outwardly and horizontally projecting flange 62 which becomes superimposed upon the casing flange 22, and by the engagement of the lower end of the cylindrical side wall 61 with the upwardly exposed U-shaped ends (see Figure 4) of the three upright members 28, 29 and 30; the latter are thus made to bottom against the bottom 14 between which and the part 60 they thus become held against displacement axially of the casing 10.

From the lower end of its cylindrical side wall 61 the member 60 merges, preferably in an upward curve, as at 63, to terminate in an open-ended cylindrical mouth or pouring spout 64.

As thus assembled, the stopper construction 35 may be inserted into the bottle neck 11 after the washer 23 (Figure 1) has been either related to the shoulder 12 or slid over the casing 10 and up against the under face of the flange 22. The parts are preferably so proportioned that the plane of the upper end of the spout 64 substantially coincides with the plane of the upper end 13 of the bottle neck 11.

By means of a suitable tool, the parts of which take into the ring-like space between the portions 61 and 64 (Figure 1) of the member 60, the lower portion of the cylindrical wall or band-like part 61 and with it an upper portion of the cylindrical wall of the casing 10, is forced or spun or bent, throughout the entire periphery, outwardly and against the downwardly and outwardly curved or tapering wall 65 of the shoulder 12, this action being accompanied by a drawing downwardly of the entire stopper construction and by a resultant dependable compression of the gasket 23 between the upper face of the shoulder 12 and the double flange 22—62.

An effective, durable and strong seal is thus achieved at the junction of the casing 10 with the bottle neck 11 and, moreover, one that is dependably tamper-proof. For example, while a secure fastening and seal may be achieved by thus spinning the upper portion of the casing 10 alone against the under wall of the shoulder 12, the construction above described in effect mechanically locks this outwardly forced portion of the casing wall in that the substantial mechanical strength and rigidity of the substantially frustoconical portion 63 of the member 60 is interposed to resist such inward movement of the outwardly forced metal of the casing 10 as would be necessary to effect upward withdrawal of the casing or stopper from the bottle neck. Furthermore, the outwardly bulging or outwardly forced part of the wall 61 of the member 60 is not only in

effect a ring or band but also a ring of angled or curved cross-section, having relatively great resistance to distortion or forced contraction, and by itself serves as a dependable lock.

5 The stopper construction is, of course, assembled to the bottle neck after the bottle or container has been filled, whereupon we achieve a closure, against spilling, of the bottle in any suitable way but preferably by the arrangement 10 shown in Figure 1. Accordingly, the bottle neck 11 is provided externally with a thread 66 to receive the thread 67 formed in the side wall of a sheet metal cap 68 under the top wall of which is fitted a gasket 69, such as cork, or the like, 15 with or without a thin sheet metal or foil member 70. The cap 68, when screwed home, brings the gasket 69—70, the latter being yieldable, into tight peripheral engagement with not only the top edge or face 13 of the bottle neck 11 but 20 also the top edge of the spout 64, effecting a dependable seal at both peripheral edges or faces.

The seal achieved at the top edge of the spout 64 stops in the first instance egress of liquid contents as, for example, when the bottle is laid 25 over on its side while the seal achieved at the bottle neck top edge 13 insures against loss of liquid contents in the event that the seal at the gasket 23 or at the spun joint between the parts 60 and 10 should spring a leak and also against 30 possible leakage at the seal between the cap gasket 69 and the spout 64. Thus, dependable insurance against leakage is achieved.

However, we might also and particularly in view 35 of the dependable seal and junction achieved, as above described, at the gasket 23 effect a closure by an arrangement shown in Figure 3a. In this modification, the spout portion 64 of the member 60 is formed to have threads, as indicated, and a threaded sheet metal cap 70, with a gasket 71 therein, may be threaded onto this 40 threaded spout 64, thus effecting a seal at the upper edge of the spout 64.

In the action and operation of the stopper construction many unique advantages and coactions 45 are achieved. For example, in effecting a pouring of the liquid contents out of the bottle, after the closure has been removed, the knife edge engagements with the ball valve 19 and the weight 20 of the flange portions 35 and 36, respectively 50 (Figures 7 and 8) insure an almost frictionless resistance to displacement of the ball and the weight under the pressure of the liquid seeking 55 egress from the container; the ball 19 is thus quickly displaced from its yieldable seat 17 and any resistance to such displacement by the weight 60 20 likewise overcome. The ball 19 is thus positioned on the knife edge parts of the flanges 32, 33 somewhat to the left of the position shown in Figure 3, and a free flow of liquid through the 65 hole 18 in the gasket washer 17 and into the casing 10 results, the thin sheet metal flanges 32, 33 occupying but a minimum of volume of the 70 space available for liquid flow.

The liquid then, in effect, divides along two 75 paths of flow, one being through the annular space E (see Figure 5) between the casing wall and the cylindrical wall 49 of the part 43, and another being through the annular space F (Figure 5) between the cylindrical wall 49 and the flange 46 of the part 44. The former path leads 80 directly to the spout 64 and the latter leads thereto but through the internal spout 50.

At the same time there may take place an 85 interchange or commingling of liquid between 90 these two paths, and that may take place through

the apertures 54, 56 and 51 (Figure 9) in the side wall of the member 43, and by way of these apertures a self-seeking distribution of flow between the two paths takes place.

As liquid is thus flowing out of the container, 5 air is entering the latter along similar paths but in reverse directions. Such a nicety of ingress of air and egress of liquid takes place by this construction that the "pour" is a steady 10 uniform substantially solid stream and the flow 15 is, moreover, very rapid.

Attempts to fill the bottle when inverted are frustrated by the buoyancy of the ball valve 19 which is hollow and which floats upwardly into engagement with its seat, thus closing off entrance to the bottle. If it is attempted to refill the bottle with the latter at an angle to the vertical, such as is indicated in Figure 3, the unbalanced weight 20, having at its peripheral edges the substantially frictionless knife edges 20 of the portions 66, 66 (Figures 8 and 6) for a support, slides and tilts into a position like that shown in Figure 3, the inclination of the portions 36, 36 and the frictionless character of the knife edges insuring dependability of these actions and hence of its action in pushing the ball 19 along its frictionless knife edges into seating position. In this connection, it will be noted that the lowermost tongues 39, 39 of the members 28, 29 and 30 are of sufficient inward 30 extent to form stops for the weight member 20.

The point contacts between the knife edges and the weight or ball also negative adhesion or adherence of the parts as might otherwise be encouraged by the wetness of the parts.

Nor can the bottle be filled by achieving a differential of pressure between its interior and the liquid attempted to be forced into it. In this connection the actions just above described initially seat the ball 19 against the yieldably 40 flexible washer or seat 17, giving it a position as shown in Figure 1.

The greater the pressure differential, the greater the pressure with which the ball 19 is forced against its seat. The inner annular portion of the washer 17 bends or yields, assuming a dished or generally frusto-conical shape, as is better shown in Figure 3, and thereby a band-like area of the washer 17 is presented to the ball 19, transforming what, excepting for the inherent softness or yieldability of the material of the washer itself, was theoretically a circular line of sealing contact into a band or zone of sealing contact of substantial area. For this purpose the inner annular portion 16 of the bottom 55 14 (Figures 1 and 3) is bent or curved downwardly or given a generally frusto-conical shape to provide a limiting support for the washer when thus flexed or bent to give the above-described contact surface of substantial area. Continued application of pressure acts still further to enlarge this zone or band of sealing contact, due to the inherent softness or yieldability of the material of the washer.

Thus, attempts to fill the bottle by attempting to force liquid into it under pressure, and this attempt may be made by reducing the pressure in the bottle below atmospheric, are dependably frustrated.

During normal use, however, the washer 17, 70 though yieldably flexible, normally assumes and retains the relationship shown in Figure 1, due to the above-described cantilever action or support, and the engagement therewith of the ball 19 is primarily along a line or circle; this in- 75

sures that the bottle contents may freely "breathe" into and out of the spaces within or above the casing 10, particularly during changes in temperature, and hence equalization of vapor pressures on the two sides of the valve seat efficiently take place without giving rise to a difference of pressure sufficient to cause the valve 19 to be held and locked against its seat.

Preferably the metal washer 21 has a relatively sharp downwardly directed lip or edge 21^a (Figure 1) which somewhat bites into or becomes embedded in the gasket-like washer 17 when the construction is assembled, as earlier above described, the two washers becoming thereby related to each other with substantially perfect concentricity. But features already above described also bring about a like concentricity of relationship between the two washers and other parts, such as the casing itself, the guideway for the valve 19 and for the weight 20, and thus initial assembly achieves coaxial alinement of these various parts. Due, however, to the lip 21^a biting into the washer 17, subsequent changes in, for example, the outside diameter of the washer 17, are precluded from allowing such a displacement in the position of the washer 17 taking place as might disturb the concentricity or coaxial alinement between the washer opening 18 and the rest of the parts such as the casing, the guideway for the ball valve 19, and the ball valve itself. The washer 17 may undergo certain changes in dimensions due to expansion or contraction caused by various conditions, such as the degree of wetness of the washer; however, the dependable connection between the metal washer 21, which is dependably centered or maintained coaxial with respect to the casing, guideway, and hence the ball valve, prevents lateral shifting of the washer 17 as a whole and causes any contractions or expansions, such as might affect the opening 18 therein, always to take place concentrically with respect to the guideway and hence the ball valve. The latter accordingly always finds the washer opening 18 and itself truly coaxial, and thus permanency of the intended or desired coactions therebetween is assured.

As already described, the range of rolling movement of the ball 19 along the knife edges provided by the flange edges 35, 35, etc., is limited not to exceed the length of the latter, and, as better appears in Figure 1, the flanges 32, 33 of the upright members hold the ball, and also the weight 20, for that matter, a substantial distance away from the inside cylindrical walls of any of the parts. These relationships, including the knife edge contacts with the ball and weight, also make virtually impossible any substantial adherence or adhesion of the ball or weight to the parts that they contact, by reason of the parts being wet by the liquid, or foreign substances that might be injected in the attempt to anchor these parts in a position to negative any of the above-described actions in preventing refilling. Also, the ball 19 and weight 20 are dependably protected against access thereto by means of an implement, instrument, or the like.

It will thus be seen that there has been provided in this invention a stopper construction in which the various objects hereinbefore noted, together with many thoroughly practical advantages, are successfully achieved. The construction is thoroughly dependable and durable, and may be inexpensively and expeditiously manufactured, particularly where the parts are made

of sheet metal; however, it will be apparent, in view of the foregoing, that many of the features and advantages of our invention may be realized in practice where materials other than metal are employed. Thus, for example, non-metallic materials may be employed, including so-called moldable materials, plastics, ceramics, or the like. Moreover, the construction is well adapted to meet the peculiar and varied conditions of practical use.

As many possible embodiments may be made of the above invention, and as many changes might be made in the embodiment above set forth, it is to be understood that all matter hereinbefore set forth, or shown in the accompanying drawings, is to be interpreted as illustrative and not in a limiting sense.

We claim:

1. A non-refillable bottle stopper construction comprising a sheet metal shell having an annular bottom supporting, in overhanging relationship to the opening therein, a yieldably flexible washer, said washer having an inner peripheral portion overhanging the inner periphery of said annular bottom whereby the former portion may yieldably flex with respect to said inner bottom periphery, said casing having a plurality of channels formed in its side walls, a ball float valve for coaction with said washer and movable into engagement with the inner peripheral portion of said washer and to flex it and thereby increase the surface of contact between said ball valve and said washer, an unbalanced weight member for coaction with said valve, guide means for said ball valve and said weight member comprising a plurality of parts having portions extending longitudinally of said casing and presented inwardly toward said float valve and weight member and having portions respectively received in said casing channels, said parts overlying said washer to hold it in place, and baffle means adjacent the other end of said casing and secured thereto for closing off the guideway formed by said plurality of parts and for holding the latter in their respective channels.

2. A non-refillable bottle stopper construction comprising a sheet metal shell having an annular bottom supporting, in overhanging relationship to the opening therein, a yieldably flexible washer, said casing having a plurality of channels formed in its side walls, a ball float valve for coaction with said washer, an unbalanced weight member for coaction with said valve, guide means for said ball valve and said weight member comprising a plurality of parts having portions extending longitudinally of said casing and presented inwardly toward said float valve and weight member and having portions respectively received in said casing channels, said parts overlying said washer to hold it in place, and a plurality of members interfitted with the upper ends of said plurality of parts for holding the latter in their respective channels and forming baffle-like means with circuitous passages to prevent access to said weight member and float valve while permitting flow of liquid through said passages.

3. A non-refillable bottle stopper construction comprising a sheet metal shell having an annular bottom supporting, in overhanging relationship to the opening therein, a yieldably flexible washer, said casing having a plurality of channels formed in its side walls, a ball float valve for coaction with said washer, an unbalanced weight member for coaction with said valve, guide means

for said ball valve and said weight member comprising a plurality of parts having portions extending longitudinally of said casing and presented inwardly toward said float valve and 5 weight member and having portions respectively received in said casing channels, said parts overlying said washer to hold it in place, baffle means adjacent the upper ends of said parts and mechanically interengaged therewith, said casing 10 having an upper portion capable of being outwardly expanded as against a shoulder of a part to which said stopper construction is to be secured, and a spout-forming member of sheet metal seated within said upper casing portion and 15 against the upper ends of said plurality of parts and capable of being also outwardly expanded and thus to be seated in the outwardly expanded upper casing portion.

4. A construction of the character described 20 comprising, in combination, a bottle neck having an inwardly extending shoulder with a gasket resting against its upper face, a non-refillable stopper construction having its upper sheet metal end annularly conformed to be outwardly con- 25 cave and to envelop said gasket and shoulder, and a sheet metal member having a band-like portion received within said upper end and sub- 30 stantially conformed thereto to lock said annular outwardly concave sheet metal end against forced 35 distortion or disengagement from said shoulder and gasket.

5. A construction as claimed in claim 4 in 40 which said sheet metal member has an upward spout-forming extension, and means for releasably sealing said spout-forming extension.

6. A construction as claimed in claim 4 in 45 which said sheet metal member has an extension to form a pouring spout whose mouth terminates in substantially the same plane as the mouth of said bottle neck, a gasket extending across the 50 bottle neck mouth and engaging both the latter and the mouth of said pouring spout, and means for releasably holding said gasket in sealing relationship to both of said mouths.

45 7. A non-refillable bottle stopper construction comprising a casing having a valve opening in its bottom and a valve coacting therewith, an unbalanced weight member coacting with said valve, a sub-assembly structure comprising a plurality 55 of substantially circumferentially spaced longitudinally extending parts forming a guideway for said valve and weight member and having passage-forming baffle means closing off said guideway and when inserted into said casing closing off the upper end thereof, and means holding 60 said sub-assembly in assembled relation to said casing, said baffle-forming means comprising a member extending transversely adjacent the upper ends of said guideway-forming parts, the latter having inward extensions to prevent contact between said weight member and said baffle member.

8. A non-refillable bottle stopper construction 65 comprising a casing having a valve opening in its bottom and a valve coacting therewith, an unbalanced weight member coacting with said valve, a sub-assembly structure comprising a plurality 70 of substantially circumferentially spaced longitudinally extending parts forming a guideway for said valve and weight member and having passage-forming baffle means closing off said guideway and when inserted into said casing closing off the upper end thereof, and means holding 75 said sub-assembly in assembled relation to said casing, said guideway-forming parts be-

ing of sheet metal and having inwardly open notches adjacent their upper ends, said baffle means including a baffle member having its marginal portions seated within said notches.

9. A non-refillable bottle stopper construction 5 comprising a casing having a valve opening in its bottom and a valve coacting therewith, an unbalanced weight member coacting with said valve, a sub-assembly structure comprising a plurality 10 of substantially circumferentially spaced longitudinally extending parts forming a guideway for said valve and weight member and having passage-forming baffle means closing off said guideway and when inserted into said casing closing off the upper end thereof, and means holding 15 said sub-assembly in assembled relation to said casing, said guideway-forming parts being of sheet metal and having inwardly open notches adjacent their upper ends, said baffle means including a baffle member having its marginal portions seated within said notches, and a second baffle member having a substantially central mouth portion and a skirt-like portion of a substantial downward extent and slotted to interfit 20 with upper end portions of said guideway-forming parts.

10. A non-refillable bottle stopper construction comprising a casing having a valve opening in its bottom and a valve coacting therewith, an unbalanced weight member coacting with said valve, a sub-assembly structure comprising a plurality 30 of substantially circumferentially spaced longitudinally extending parts forming a guideway for said valve and weight member and having passage-forming baffle means closing off said guideway and when inserted into said casing closing off the upper end thereof, and means holding 35 said sub-assembly in assembled relation to said casing, the means holding said sub-assembly in assembled relation to said casing comprising means secured to said casing adjacent its upper end and forming a stop against movement 40 of said sub-assembly out of said casing.

11. A non-refillable bottle stopper construction comprising a casing having a valve opening in its bottom and a valve coacting therewith, an unbalanced weight member coacting with said valve, a sub-assembly structure comprising a plurality 45 of substantially circumferentially spaced longitudinally extending parts forming a guideway for said valve and weight member and having passage-forming baffle means closing off said guideway and when inserted into said casing closing off the upper end thereof, and means holding 50 said sub-assembly in assembled relation to said casing, the means holding said sub-assembly in assembled relation to said casing comprising a member secured to the casing adjacent the upper end thereof and having a pouring opening 55 therein.

12. A non-refillable bottle stopper construction comprising a casing having a valve seat and a movable valve member coacting therewith, an unbalanced member in said casing for coaction with said valve member, said unbalanced member being unbalanced so that, when the stopper construction is tilted, the unbalanced member is tiltable in a direction to move said valve member toward its valve seat, and means forming a guideway for holding said unbalanced member 70 within said casing and in coacting relationship to said valve member and comprising a plurality 75 of individual parts spaced about the interior of said casing and each presenting to said unbalanced member a relatively sharply defined edge,

5 to hold said unbalanced member spaced from the walls of said casing and to guide it in its movement relative to said valve member, and means holding said individual parts in assembled relationship to said casing to form said guideway.

10 13. A construction of the character described comprising, in combination, a bottle neck having an inwardly extending shoulder, a non-refillable stopper construction in said bottle neck and comprising a casing whose upper end is annularly conformed to be outwardly concave and to envelop said shoulder, and valve means and baffle means in said casing, and means for holding 15 said valve means and baffle means from movement outwardly of said casing and comprising a band-like member received within the upper end of said casing and substantially conformed thereto to lock said annular outwardly 20 concave end against forced distortion or disengagement from said shoulder and whereby said band-like member is itself anchored in position, said band-like member having means blocking

movement of said baffle means upwardly out of said casing.

14. A construction of the character described comprising, in combination, a bottle neck having an inwardly extending shoulder, a non-refillable stopper construction in said bottle neck and comprising a casing whose upper end is annularly conformed to be outwardly concave and to envelop said shoulder and valve means and valve-guiding means in said casing, and means for holding 10 said valve means and valve-guiding means from movement outwardly of said casing and comprising a band-like member received within the upper end of said casing and substantially conformed thereto to lock said annular outwardly concave end against forced distortion or disengagement from said shoulder and whereby said band-like member is itself anchored in position, said band-like member having means blocking movement of said valve-guiding means 15 upwardly out of said casing.
